UNITED STATES PATENT OFFICE.

ALEXANDER C. YUDELSON, OF CHICAGO, ILLINOIS.

CONVERTIBLE COAT AND JACKET.

1,125,789.

Specification of Letters Patent. Patented Jan. 19, 1915.

Application filed April 17, 1911. Serial No. 621,466.

To all whom it may concern:

Be it known that I, ALEXANDER C. YUDELSON, a citizen of the United States, and a resident of the city of Chicago, in the county of Cook and State of Illinois, have invented certain new and useful Improvements in Convertible Coats and Jackets; and I do hereby declare that the following is a full, clear, and exact description of the same, reference being had to the accompanying drawings, and to the numbers of reference marked thereon, which form a part of this specification.

This invention relates to improvements in convertible coats and jackets, and is more particularly illustrated in a sweater coat constructed of a knitted fabric.

The object of the invention is to afford a lapel and collar construction in connection with such a coat whereby the coat may be worn with open front and collar, or with the collar adjusted to afford the military effect and inclosing the neck.

It is also an object of the invention to afford a construction whereby the set or fit of the coat is not affected by the adjustment of the collar to either of its two positions.

It is a further object of the invention to afford a construction of the class described, in which the number of pieces or parts required to effect the convertible construction is reduced to a minimum, and in which advantage is taken, to some extent, of the elasticity of the fabric to afford a satisfactory result.

The invention consists in the matters hereinafter described and more fully pointed out and defined in the appended claim.

In the drawings: Figure 1 is a front elevation of an article of apparel or sweater coat embodying my invention, showing the collars and lapel in open adjustment. Fig. 2 is a similar view with the collar turned up and closed, to afford a military effect. Figs. 3, 4, 5 and 6 are diagrammatic views, illustrating the cutting and attachment of the parts, and illustrating operation. Fig. 7 is a fragmentary front elevation, showing the coat closed to afford the military neck and with the corners or end portions of the collar partly turned back.

As shown in the drawings: 1, indicates the garment, which may be a sweater, sweater coat or the like, constructed of knit fabric or, of course, other materials may be employed.

2, indicates the lapel, and 3, the collar, which, in Fig. 1, is shown adjusted to afford the open front and with the top of the collar turned down upon the shoulders affording a broad rear flap.

Referring to Figs. 3 to 7 inclusive, 3, indicates the collar, 4, one of the sweater or coat fronts, and 5, a longitudinal strip secured by sewing, weaving, or knitting along the front edge of the front portion 4. The collar is cut at each end from its under edge upwardly and outwardly to afford an oblique line 6, and the front 4, is cut at its upper end to afford a point 7, which coincides with the point at the under edge of the collar from which the line 6, inclines upwardly. At each side of said point 7, the front is cut away and at its front edge is considerably shorter than at said point, as shown in Fig. 3. The longitudinal strip 5, is cut at its rear edge to afford a long point 8, which coincides approximately with the middle of the inclined line or edge 6, on the collar. Said strip is of a width for the front edge thereof to coincide approximately with the end of the collar. At said upper extremity, said strip is cut away from said point 8, forwardly, as shown in Fig. 3. In finishing the garments, the parts are sewed, stitched or knitted together, as shown in Fig. 4, the effect being to produce a tension at the end of the collar and forward edge of the strip 5, slightly extending the fabric, while at the point 8, and point 7, a slight fullness results. Of course, this extension or expansion at the one position and the slight fullness at the other is not readily apparent, and, in fact, not apparent at all unless the garment be carefully examined.

It is sufficient, however, for the point 8, to serve, in a sense, as a fulcrum point, so that when the garment is folded low on the shoulders and neck, as shown in Fig. 1, the fabric may yield sufficiently and without appreciably distorting any stitch to insure a close fit, said collar in that case (owing to the construction) folding smoothly over the shoulders with the broad flap of the collar turned down the back, as shown in Fig. 3, and fitting closely thereto.

When it is desired to use the coat and to obtain the military effect, the collar is folded longitudinally, as shown in Figs. 2, 6 and 7, and the ends thereof are drawn together in front and are secured together by a hook and eye 11, or any suitable fastening

means, as shown in Figs. 3 and 7. In that instance, the shape of the lower edge of the collar and the method of attaching the fronts of the garment thereto, permits the 5 garment to lie perfectly smooth.

In the construction shown in Fig. 7, the 10 folds or flaps 9, and 10, at the ends of the collar, are turned upwardly and away to expose the hook and eye 11, whereby the front of the garment is closed.

Of course, any suitable means may be 15 used for fastening the garment in either position. Undoubtedly, other garments than knit garments may be constructed as herein described, and I do not purpose limiting myself otherwise than necessitated by the prior art.

I claim as my invention:

A coat, embracing a front portion, a strip 20 secured to the longitudinal edge thereof and cut at its edge where it is joined thereto longer than the edge of said front portion to afford a long point, and a collar cut at its

under edge at its end upwardly and outwardly to afford an oblique line, said front 25 portion being similarly cut diagonally at its upper end to afford a point, and the upper end of said strip being cut away forwardly, the cut away portions of said front portion and strip being united to the oblique 30 portion of said collar, whereby a tension is produced at the meeting point of the end of said collar and the outer edge of said strip, while a fullness is produced at the point of junction of the outer edge of the 35 front portion with said collar and at the point where the oblique portion of said collar begins.

In testimony whereof I have hereunto 40 subscribed my name in the presence of two subscribing witnesses.

ALEXANDER C. YUDELSON.
